DESIGN FOR A BED URINAL

William Bal, Newark, and John T. Simpson,
Fair Haven, N. J.

Application December 19, 1942, Serial No. 109,068

Term of patent 14 years

To all whom it may concern:

Be it known that we, William Bal, a citizen of the United States, residing at Newark, in the county of Essex and State of New Jersey, and John T. Simpson, a citizen of the United States, residing at Fair Haven, in the county of Monmouth and State of New Jersey, have invented a new, original, and ornamental Design for a Bed Urinal, of which the following is a specification, reference being had to the accompanying drawing, forming a part thereof.

In said drawing Fig. 1 is a side elevational view;

Fig. 2 is a top plan view, and

Fig. 3 is a front end elevational view of a bed urinal embodying our new design.

We claim:

The ornamental design for a bed urinal, as shown.

WILLIAM BAL.
JOHN T. SIMPSON.
